UNITED STATES PATENT OFFICE.

MASON COMBS, OF PINEVILLE, KENTUCKY.

DROPPER.

Application filed July 23, 1924. Serial No. 727,766.

To all whom it may concern:

Be it known that I, MASON COMBS, a citizen of the United States, residing at Pineville, in the county of Bell and State of Kentucky, have invented certain new and useful Improvements in Droppers, of which the following is a specification.

This invention relates to closures for containers and its object is to provide a closure which will be especially adapted for cans containing anesthetics or medical syrups and compounds, and by the use of which the contents of the containers will be kept in a sanitary condition, guarded against loss, and permitted to escape when desired in easily regulated quantities. The invention is illustrated in the accompanying drawing and will be hereinafter fully set forth.

20 In the drawing:

Figure 1 is a view, partly in elevation and partly in section, of one embodiment of my invention;

Fig. 2 is a perspective view of the form of the invention illustrated in Fig. 1 with the cap removed;

Fig. 3 is a perspective view showing another embodiment of the invention;

Fig. 4 is an enlarged detail perspective view of the plunger shown in Figs. 1 and 2, and

Fig. 5 is a similar view of the plunger shown in Fig. 3.

That form of the invention illustrated in Figs. 1 and 2 is intended more particularly for containers in which anesthetics are supplied, a portion of the body of the container being shown at 1. This body 1 is sealed after being filled, and the top 2 is provided centrally or at such other point as may be preferred with a neck 3 which is preferably formed integral with the top, and it will be readily noted upon reference to Fig. 1 that this neck is open at its outer end but is closed by the top of the container at its inner or lower end. A stopper 4, which is preferably of the construction disclosed in Letters Patent No. 1,478,891, granted to me December 25, 1923, is fitted within the neck 3 so that it will be retained in and by the same and will seat upon the top 2. This stopper, as fully set forth in my said patent, consists of inner and outer sections which are pivotally connected by a rod or pin 5 extending axially through the sections, and the sections are provided in their circum-

ferential faces with longitudinal grooves 6 which are adapted to aline or be placed out of alinement by rotating the outer section relatively to the inner section. When the container is filled and ready for the customer, the grooves of the stopper sections are in alinement and a plunger 7 is seated in the grooves at one side of the stopper. It will be noted, upon reference to Fig. 1, that the plunger fits snugly within the groove and between the body of the stopper and the neck, and the plunger is of such length that its upper end will project slightly above the top or outer end of the stopper while its lower end will rest upon the top or head of the can or container. The lower end of the plunger is properly shaped or formed to provide a piercing point 8 and a stop shoulder 9 whereby upon the application of force to the plunger the point may be easily driven through the top of the can to puncture the same, and the extent of penetration will be limited by contact of the stop shoulder with the top of the can, as will be understood. The neck 3 is provided at its upper end externally with threads 10 and with an annular rib or flange 11 which constitutes a stop to limit the closing movement of a cap 12 which is engaged over the neck 3 to house the stopper and the plunger, as clearly shown in Fig. 1.

The device is supplied with the parts arranged as shown in Fig. 1, the cap serving to protect the stopper and the plunger from an accumulation of dust or from any contamination due to careless or unnecessary handling. The cap, when in place, also prevents access to the plunger so that the can cannot be prematurely punctured by accidental blows upon the plunger and, consequently, undesired escape and loss of the anesthetics is prevented. When the anesthetic is to be administered, the cap 12 is removed and a very light blow or pressure applied to the plunger so as to drive the point 8 into and through the top of the can and thereby form a perforation in the latter. The plunger is then withdrawn so that the grooves in which it was seated will provide a clear channel for the escape of the anesthetic. The rapidity of escape may be regulated by turning the outer section of the stopper so that the groove 6 therein will be disposed more or less out of alinement with the groove in the inner member of the stopper and, consequently, the channel provided

by the grooves will be more or less restricted. After the anesthetic has served its purpose, the outer section of the stopper may be rotated so that the grooves will be entirely 5 out of alignment and in such position the outer stopper section will form a closure to block and prevent flow through the grooves. The cap may then be returned to its position upon the neck and any unused portion 10 of the anesthetic which may remain in the container will be saved. The construction and arrangement of parts of my improved closure minimizes the area of the cork exposed to contact with the ether or other anesthetic and, consequently, deterioration of the anesthetic is minimized. It will be understood, of course, that the plunger, before being put aside, is operated through the grooves at both sides of the dropping stopper so 20 that two perforations will be formed in the container top, that perforation which is in the lower position when the can is tipped serving as an outlet for the anesthetic, while the other perforation will serve as an inlet 25 for air to prevent the formation of a vacuum in the container and, consequently, will insure a steady flow of the ether in such quantities as the physician or anesthetist may deem proper.

30 In Fig. 3 I have shown an embodiment of the invention which is more particularly adapted for dispensing heavy syrups or other medical compounds which require larger openings or passages for their discharge 35 from the container. In this form of the invention, the container 20 is provided with two necks 21 and 22 which are of different size but are identical in construction with the neck shown in Figs. 1 and 2 and here- 40 tofore described. A stopper 23 is fitted in the neck 21 and a stopper 24 is fitted in the neck 22, these stoppers being identical in construction but varying in size. The stoppers 23, 24 are formed in two sections or 45 members rotatably connected in the same manner that the stopper sections shown in Figs. 1 and 2 are connected, but instead of having grooves as shown in the first de- 50 scribed form of the invention they are flattened or cut-away longitudinally at one side so that a space is provided between the stopper and the neck in which it is fitted to receive a plunger 25. As shown clearly in Fig. 5, this plunger is provided with a flat 55 face 26 adapted to seat against the flat face of the stopper and has an arcuate face 27 which fits within and against the wall of the neck, the lower end of the plunger being tapered, as shown at 28, whereby it may 60 readily pierce the top of the container when force is applied to the plunger. To prevent the plunger being driven through the neck to an unnecessary extent and being thereby rendered difficult of withdrawal, a 65 stop lip or shoulder 29 is formed at the up-

per end of the plunger upon the flat side of the same to project over the stopper and abut the upper end thereof when the plunger is depressed. When the container is filled and supplied to a customer, each neck 70 21 or 22 is engaged by a cap 30 or 31 so that the parts will be protected and the plunger will be guarded against accidental blows and premature puncturing of the top of the container will be avoided.

75

The use and operation of this form of the invention is essentially the same as the operation of the first described form. When the contents of the container are to be withdrawn, the plungers are forced into the top 80 of the container and then withdrawn so that openings or channels will be produced through which the liquid in the container may flow and air also be admitted to the container to prevent the formation of a 85 vacuum and assure the proper steady flowing of the liquid. It will be noted that the flat faces of the stoppers are disposed at relatively diametrically opposite points and it is intended when the contents of the container are being drawn that the container should be so disposed as to place the larger neck and stopper at the lower point while the smaller neck and stopper will be at the higher point. By thus disposing the parts, 90 the channel furnished through the larger neck for the discharge of the liquid will be at the under side of the stopper while the channel for the admission of air will be at the top of the upper smaller stopper. By 95 rotating the outer sections of the stoppers relative to the inner sections thereof, the effective cross sectional area of the channels may be varied and the rate of flow thus controlled. This last described form of the invention is particularly desirable for containers storing heavy syrups and oils or other medical compounds which are usually re- 100 tailed in very small quantities, as the portions of the liquids remaining in stock are effectively protected against deterioration and the containers easily kept in a sanitary condition at all times.

105 It will be understood that the invention is not confined to the use of the particular stopper disclosed in my aforesaid Letters Patent but an ordinary cork stopper may be fitted in the neck after the plunger has been used, and the plunger may be retained in the neck by any convenient preferred 110 means.

115 Having thus described the invention, I claim:

1. Means for the purpose set forth comprising a container having a sealed top, a neck on the top of the container normally closed by the said top, a stopper fitted in the neck and constructed to permit and regulate the flow from the container, means 120 fitted between the stopper and the neck to 125 130

puncture the top of the container, and means for normally preventing operation of the last-mentioned means.

2. A container having a normally sealed top, a neck on the top, a dropping stopper fitted snugly within the neck, a puncturing element fitted within the neck and held by the stopper, and a cap fitted on the neck and housing the puncturing element and the stopper.

3. A container having a normally sealed top, a neck upon the top, a stopper fitted in the neck, a puncturing element fitted within the neck at the side of the stopper and normally resting on the top of the container, the puncturing element normally projecting beyond the end of the stopper and having its lower end constructed to penetrate the top of the container upon the application of

force to its projecting upper end, and means for limiting the puncturing movement of the said element.

4. A container having a normally sealed top, a neck on said top, a stopper fitted within the neck, a puncturing element fitted within the neck at the side of the stopper and normally bearing upon the top of the container with its outer end projecting beyond the outer end of the stopper, and a cap removably fitted upon the neck and housing the stopper and the puncturing element, the neck being provided with a stop to limit the movement of the cap whereby to prevent the application of pressure to the puncturing element.

In testimony whereof I affix my signature.

MASON COMBS. [L. s.]
